(57) CLAIM

The ornamental design for a combined printer and scanner, as shown and described.

DESCRIPTION

FIG. 1 is a perspective view of a combined printer and scanner showing our new design;

FIG. 2 is another perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side elevational view thereof;

FIG. 8 is a left side elevational view thereof; and,

FIG. 9 is a cross-sectional view taken along line 9—9 of FIG. 3.

The broken lines are shown for illustrative purposes only and form no part of the claimed designs.

1 Claim, 9 Drawing Sheets
